UNITED STATES PATENT OFFICE.

AUGUST F. LUZZI, OF HOUSTON, TEXAS, ASSIGNOR TO J. B. AKERS, OF BRECKENRIDGE, TEXAS.

TRUSS.

Application filed December 30, 1926. Serial No. 157,957.

This invention relates to new and useful improvements in a truss.

One object of the invention is to provide a truss of the character described including an adjustable pad so mounted that it may be readily adjusted to any position, relative to the abdominal wall and there secured in a fixed position.

Another object of the invention is to provide a truss of the character described having a novel type of hernial pad, of novel construction which may be cheaply and easily produced and readily adjusted, and which may be worn with comfort.

With the above and other objects in view this invention has particular relation to certain novel features of construction, arrangement of parts and use, an example of which is given in this specification and illustrated in the accompanying drawings, wherein Figure 1 shows a front elevation of a complete truss, as applied to the body of a wearer.

Figure 2 shows an enlarged transverse sectional view of the hernial pad.

Figure 3 shows an enlarged fragmentary side elevation of the body clamp, and

Figure 4 shows a sectional view thereof taken on the line 4—4 of Figure 3.

Referring now more particularly to the drawings, wherein like numerals of reference designate similar parts in each of the figures the numeral 1 designates a body clamp, preferably formed of a flexible steel rod, or other suitable flexible material and

35 U-shaped in general contour so as to clamp around one side of the body. Attached to the rear end of this body clamp is a back pad 2 designed to rest against the back of the wearer and the free end of the front

40 arm of the body clamp carries the hernial pad designated generally by the numeral 3. This body clamp is formed of two sections whose adjacent ends overlap and are fitted through a clamp collar 4 and are retained therein by means of a suitable clamp screw

45 5 in an obvious manner. This screw may be loosened and the body clamp adjusted as desired.

The numeral 6 designates the hernial pad 50 which is preferably disc-like in form and is composed of soft rubber or other suitable soft material. This pad is enclosed in a fabric sack or cover 7. The outer side of

the pad 6 has a concaved seat in which rests the convex face of the concavo-convex nut 8 and there is a disc-like clamp plate 9 backing the disc 6 whose margin 10 is overturned toward said disc and whose central portion is of concavo-convex formation to conform to the contour of and to seat within the concave surface of the nut 8, and said disc has a relatively large central opening 11. There is a hemispherical clamp block 12 having its convex face fitted within the concaved portion of the clamp plate 9 and a clamp bolt 13 is fitted through a central bearing in the block 12 and threaded through the nut 8, said bolt having an enlarged head 14 and this bolt clamps the adjacent parts in assembled relation and its outer end is 70 formed with a socket 15 to receive a suitable socket wrench for manipulating the same. There is an annular clamp washer 16 whose inner margin 17 is outwardly turned and rests against the margin of the nut 8 and 75 whose outer margin clamps the adjacent margin of the fabric covering 7 between it and the disc 9 so as to hold the pad 6 in assembled relation with its supporting means. The adjacent end of the body clamp 1 is 80 formed with an eye 18 which surrounds the reduced inner side of the head 14 and is clamped between said head and the clamp block 12 and this supports the hernial pad in position.

It is obvious that a ball joint is formed between the clamp block 12 and the disc 9 to the end that when the clamp bolt 13 is loosened said pad may be adjusted in any desired position, one adjusted position being 90 indicated by dotted lines in Figure 2, and when said clamp bolt is tightened the hernial pad will be held securely in said adjusted position. In making these adjustments the nut 8 maintains itself in fixed relation with 95 the clamp block 12, the clamp washer 16 being forced by said nut into eccentric position relative to the clamp plate 9 but maintaining itself in clamping relation with the margin of the fabric covering 7 and all 100 parts are securely held in the selected position when said clamp bolt 13 is tightened. The body clamp 1 is retained in position by means of the strap 19 fastened to the rear side of said clamp above the body pad 2 and 105 attached to the front side of the clamp 1 ad-

jacent the hernial pad and this strap may be adjusted to the body by means of the usual buckle 20.

What I claim is:

1. In a truss a hernial pad having a sack-like cover, a clamp plate and a clamp washer between which the margin of said cover is clamped, a clamp block and a clamp nut between which said plate is clamped, the outer margin of said nut resting against the inner margin of the washer, a clamp bolt passing through the block and onto which said nut is threaded.
2. In a truss a hernial pad having a sack-like cover, a concavo-convex clamp nut with its convex side adjacent said pad, a clamp plate having a concavo-convex central portion which fits within the concave side of said nut, a clamp block fitted into the concaved portion of said plate, a clamp washer whose inner margin rests against the margin of said nut, said plate and washer clamping the margin of the pad cover between them, a clamp bolt passing through said block and plate and having a threaded connection with said nut.
3. In a truss a hernial pad having a sack-like cover, a concavo-convex clamp nut abutting said pad and having its convex side adjacent said pad, a clamp plate having a concavo-convex portion which fits within the concave side of said nut, a clamp block fitted into the concaved portion of said plate, a clamp washer whose inner margin rests against the margin of said nut, said plate and washer clamping the margin of the pad cover between them, a clamp bolt passing through said block and plate and having a threaded connection with said nut, the outer end of said bolt having an enlarged head and a body clamp, one end of which is formed with an eye which surrounds said bolt and is clamped between said head and block.
4. In a truss a hernial pad, a clamp nut adjacent the pad, a clamp plate adjacent the outer side of said nut, a clamp washer around

and in contact with the nut and held in clamping relation with the plate by said nut, a pad covering having its margin clamped between the plate and washer, a clamp block resting against the outer side of said plate, a clamp bolt passing through said block and plate and with which the nut has a threaded connection.

5. In a truss a hernial pad, a clamp nut adjacent the pad, a clamp plate adjacent the outer side of said nut, a clamp washer around an in contact with the nut, said nut forming the only means for holding the washer in clamping relation with said plate, a pad covering having its margin clamped between the plate and washer, a clamp block resting against the outer side of said plate, a clamp bolt passing through said block and plate and with which the nut has a threaded connection and a flexible body clamp to one end of which the outer end of the bolt is connected.

6. In a truss a pad having an annular free margin, a clamp plate forming a rigid backing for the pad, the central portion of the clamp plate having an opening with the margin of the plate around said opening being curved inwardly toward the pad and the outer margin of said clamp plate overlying said annular free portion of the pad, a clamp block having a convex face which works against the inwardly turned margin of said clamp plate, an annular clamp washer whose outer margin fits against the inner side of the annular free margin of said pad, said washer having a central opening with the margin around said central opening turned outwardly toward said clamp plate, a nut having a bearing against the inner side of said outwardly turned margin of said washer and a clamp bolt fitted through said clamp block and having a threaded connection with said nut.

In testimony whereof I have signed my name to this specification.

AUGUST F. LUZZI.
